UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SPOOL-HOLDER.

1,347,843.

Specification of Letters Patent.

Patented July 27, 1920.

Original application filed February 8, 1917, Serial No. 147,296. Divided and this application filed October 30, 1918. Serial No. 260,256.

To all whom it may concern:

Be it known that I, ALBERT H. DE VOE, a citizen of the United States, residing at Westfield, in the county of Union and State 5 of New Jersey, have invented certain new and useful Improvements in Spool-Holders, of which the following is a specification, reference being had therein to the accompanying drawings.

10 This invention relates to a spool-holder, more particularly to one for use with a power-stand such as that shown in my co-pending application Serial No. 147,296, filed February 8, 1917, of which this application 15 is a division.

The objects of the invention are to provide a spool-holder which is simple, easily adjusted and readily attached or removed.

In its preferred form the invention comprises 20 a spider-frame having a socket in which is adjustably secured a standard having at its lower end a cross-member carrying a desired number of spool-pins. At the upper end of the standard is a second cross-member 25 sustaining guide-loops corresponding in number to the spool-pins. In the particular embodiment shown the holder is adapted for support on the brace-rods connecting adjacent sections of a power-stand, 30 but it is obvious that it may be supported in many other ways.

In the accompanying drawings, Figure 1 is a front elevation of a power-stand with the spool-holders attached, parts being 35 broken away. Fig. 2 is a side elevation with parts in section. Fig. 3 is a perspective view of the supporting spider of a spool-holder, showing the manner in which it is carried by the brace-rods of the power-stand.

40 Referring to the drawings, 1 indicates adjacent columns of a power-stand, the lower ends of the columns being secured to a floor in any desired manner. At the head of each column is carried a housing 2 in 45 which are mounted opposed power-transmitters, each of which is belt connected to a sewing machine 3 mounted on a shelf 4 carried by the column. A single shaft 5 actuates all of the power-transmitters and is 50 driven by a pulley 6 from which a belt 7

leads to a main drive-shaft (not shown). The housings 2 of adjacent columns are connected by an inverted T-beam 2' which serves as a support for the shaft-hanger 8. A pair of brace or tie-rods 9 also extend 55 between adjacent housings. These tie-rods 9 in addition form a convenient supporting means for the plural-armed spider-frames 10 of the spool-holders. Each arm of a frame has a hooked free end 11 adapted to 60 engage one of the rods 9, and at one side of the center of the frame there is formed a socket 12 in which is secured by set-screws 13 a vertical standard 14. At the lower end of the standard 14 is secured by the set-screw 15 the socket 16 of a cross-member 17, and on the cross-member are mounted a desired number of spool-holders 18 having vertical spool-pins 19 adapted to receive thread-spools. At its upper end the standard 70 is provided with a second cross-member 20 carrying guide-loops 21 corresponding in number to the spool-holders.

In use the spider-frame is disposed with the hooked ends 11 of its arms in engagement with the tie-rods 9, and the thread is led from the spools on the pins 19 to the respective guide-loops 21 and thence to the sewing machine.

Having thus set forth the nature of the 80 invention, what I claim herein is—

1. In combination, a spider-frame, means carried thereby for supporting said frame, a socket carried by said frame, a standard adjustable in said socket, and spool-holding 85 and thread-guiding means carried by said standard.

2. In combination, a frame comprising a socket and diverging arms, means for supporting said frame carried by said arms, a standard adjustable in said socket, and spool-holding and thread-guiding means carried by said standard. 90

3. In combination, a frame comprising a socket and hooked arms extending therefrom, a standard adjustable in said socket, a spool-holder secured to one end of said standard, and a thread-guide secured to its other end. 95

4. In combination, a plurality of hooks 100

adapted to engage a support, arms depending from said hooks, and a spool-holder and thread-guide adjustably secured to said arms.

5. In combination, a spider-frame comprising a socket provided with hooked arms extending therefrom whereby the spider-

frame may be supported, a standard adjustably secured in said socket, and spool-holding and thread-guiding means carried by said standard.

In testimony whereof, I have signed my name to this specification.

ALBERT H. DE VOE.
